(57) CLAIM

I claim the ornamental design for a glove, as shown and described.

DESCRIPTION

FIG. 1 is a perspective view of a glove showing my new design;

FIG. 2 is a front perspective view thereof;

FIG. 3 is a rear perspective view thereof;

FIG. 4 is a right side elevation view thereof;

FIG. 5 is a left side elevation view thereof;

FIG. 6 is a top view thereof; and,

FIG. 7 is a bottom view thereof.

The broken lines shown in the drawings depict stitching that forms part of the claimed design.
